Primary Examiner — Darlington Ly

(57) **CLAIM**

The ornamental design for a personal three-wheeled vehicle, as shown and described.

DESCRIPTION

1.-2. Personal Three-Wheeled Vehicle

1.1 is a rear view of the personal three-wheeled vehicle showing my new design.

1.2 is a left-side view thereof.

1.3 is a top view thereof.

1.4 is a perspective view thereof.

1.5 is a right-side view thereof.

1.6 is a front view thereof.

2.1 is a rear view of the personal three-wheeled vehicle showing my new design in accordance to an alternate embodiment in which the floor board is raiseable to a raised position.

2.2 is a left-side view thereof in which the floor board is not in a raised position.

2.3 is a top view thereof in which the floor board is not in a raised position.

2.4 is a perspective view thereof in which the floor board is in a raised position.

2.5 is a right-side view thereof in which the floor board is in a raised position.

2.6 is perspective view thereof in which the floor board is not in a raised position.

2.7 is a right-side view thereof in which the floor board is not in a raised position.

(Continued)

2.8 is a front view thereof in which the floor board is not in a raised position.
